UNITED STATES PATENT OFFICE

SAMUEL M. DICK, OF PASADENA, CALIFORNIA

LIQUID CARBONATOR

Application filed August 1, 1929. Serial No. 382,810.

The invention aims to provide an exceptionally small, compact, light, inexpensive and efficient carbonator for various liquids.

In attaining the above object, a further aim is to make novel provision for conditioning the carbonator for handling relatively thin liquids such as water, dilute juices, etc., or for handling heavier liquids such as milk or buttermilk or more or less viscous liquids, 10 for instance, fruit juices.

A still further object is to provide a carbonator relying to a large extent for its efficiency, upon passage of intermingled liquid and carbonating gas jointly through a multiplicity of perforations, a plurality of perforated mixers being preferably employed through which the intermingled liquid and gas are successively passed under pressure.

A still further aim is the provision of novel 20 means for initially intermingling the carbonating gas with the liquid to be carbonated.

With the foregoing and minor objects in view, the invention resides in the novel subject matter hereinafter described and claimed, 25 description being accomplished by reference to the accompanying drawings.

Fig. 1 is a vertical sectional view through one form of carbonator constructed in accordance with my invention.

30 Fig. 2 is a top plan view.

Fig. 3 is a horizontal sectional view on line 3—3 of Fig. 1.

Fig. 4 is a detail vertical sectional view on line 4—4 of Fig. 2.

35 Fig. 5 is a sectional view showing a removable perforated cap having relatively coarse perforations, said cap or any of a plurality of similar caps having perforations of different size, being interchangeably useable with the similar cap shown in the upper portion of Fig. 1.

Fig. 6 is a plan view of a partition having relatively coarse perforations, which partition or any of a number of similar partitions 45 having perforations of different sizes, may be interchangeably used with the more finely perforated partition shown in the upper portion of Fig. 1.

The form of construction herein illustrated 50 will be rather specifically described, with the

understanding that within the scope of the invention as claimed, numerous variations may be made.

The numeral 7 on the drawings denotes a tank to contain the liquid to be carbonated, 55 said tank having a tightly fitting closure 8 held in place by the bolts 9 or any other desired means. Extending through the closure 8 is a pipe or the like 10 for conducting a gas under pressure into the upper portion 60 of the tank 7 for the purpose of driving the liquid from this tank through a pipe 11 into a carbonating chamber 12 formed by the interior of a vertically elongated container 13, said container being supported by the closure 65 8 in the present showing. As it is the sole function of the tank 7 to contain the liquid and permit placing thereof under pressure for discharge through the pipe 11, it will be obvious that if other provision be made for 70 supplying the liquid to the pipe 11 under pressure, the tank 7 will not be necessary, in which case, the container 13 would of course be supported in some other adequate way. As both of these suggested changes involve 75 only mechanical skill, they have not been shown in the drawings.

In the present showing, the container 13 is formed of upper and lower sections 14—15 respectively, the lower section being secured 80 tightly in an opening 16 in the closure 8 and projecting somewhat above said closure, while the lower end of the section 14 surrounds the projecting upper end of section 15 and rests upon a gasket 17 supported 85 by the closure 8. A horizontal bar 18 is centrally secured to the container section 14 and is provided near its ends with notches 19 engaging clamping screws 20 which are threaded into the upper ends of standards 90 21 rising rigidly from the closure 8. By loosening the set screws 20, the bar 18 and container section 14 may be turned sufficiently to disengage said bar from said screws, whereupon the aforesaid section 14 and the 95 bar 18 may be bodily removed from the remainder of the apparatus, said bar then constituting a handle for said section 14. This operation is performed when conditioning the liquid and gas mixing means according 100

to the character of the liquid to be carbonated, as will hereinafter appear.

The pipe 11 passes through and is fluid-tightly secured in an opening 22 in the lower end of the container section 15, the lower end of this pipe being swelled at 23 in the present showing, into bell formation and having openings 24 through which the liquid from the tank 7 enters said pipe. A gas supply pipe 25 which passes through and is carried by the closure 8, enters the bell or the like 23 through a notch 26 therein, said pipe 25 being provided with perforations 27 within the swelled portion or bell 23 for directing carbonating gas under pressure from any desired source, into the liquid in the pipe 11, thereby effecting initial intermingling of the liquid to be carbonated with the carbonating gas, and this liquid and gas jointly rise through the pipe 11 to be further intimately mixed, received in the lower portion of the chamber 12 in a thoroughly carbonated condition, and eventually discharged through a pipe 28 leading from the lower end of the container 13, said pipe 28 being here shown as passing through and carried by the closure 8.

To insure intimate mingling of the gas and liquid ascending through the pipe 11, I provide a central longitudinal core 29 in said pipe, which core may well be a blind continuation of the pipe 25. This core thins the stream of liquid ascending through the pipe 11 and the carbonating gas discharged into this thinned stream from the perforations 27, thoroughly mingles with the liquid.

Mounted upon the upper extremity of the pipe 11, within the upper portion of the container 13, is a gas and liquid mixer 30 having a multiplicity of perforations 31 through which the intermingled gas and liquid from the pipe 11 are jointly discharged, so that further and more intimate mixture is obtained. Extending across the chamber 12, below the mixer 30, is a final gas and liquid mixing, perforated partition 32. After the gas and liquid pass downwardly through this partition in seeking the discharge pipe 29, they have produced a thoroughly carbonated liquid which is discharged through said pipe 28.

At least the perforated portion of the mixer 30 is removable to permit substitution of a similar portion having perforations of a different size, best adapted to the liquid to be carbonated. Similarly, the partition 32 is removable and for it a partition having perforations of a proper size, may be substituted. In the present showing, the hollow mixer 30 embodies a lower section 33 and a removable upper section or cap 34 removably threaded at 35 upon said lower section 33, the latter being removably threaded at 36 upon the upper extremity of the pipe 11. When the upper container section 14 is re-

moved in the manner above described, the cap 34 is accessible and may readily be removed by hand. Then, another cap such as 34^a (Fig. 5) may be substituted for said cap 34. The cap 34^a is provided with perforations 31^a of a larger size than the perforations 31, being usable for heavier fluids. Obviously, any desired number of caps such as 34 and 34^a may be employed, with perforations of different sizes, and one cap or another may be applied to the lower section 33 of the mixer 30, according to the nature of the liquid to be carbonated.

At 32^a in Fig. 6, I have shown a partition which may be substituted for the partition 32, said partition 32^a having perforations 37^a of larger size than the perforations 37 of said partition 32. Any desired number of the partitions such as 32 and 32^a may be employed, having perforations of various sizes, and the partition most suitable for the liquid to be carbonated, may be installed, removal of one partition and substitution of another of course entailing removal of the upper container section 14, in the manner above explained.

I prefer to provide each partition such as 32 or 32^a, with a central opening 38 through which the upper portion of the pipe 11 passes, and to provide said pipe with an upwardly facing shoulder 39 upon which the partition is clamped by the lower extremity of the lower section 33 of the mixer 30. This constitutes a simple and inexpensive, yet an efficient manner of mounting the partition and allows one to be removed and another quickly and easily substituted.

In the operation of the carbonator, the liquid to be carbonated flows upwardly through the pipe 11 (whether from the tank 7 or from some other source) and in this pipe, the carbonating gas is initially intermingled with the liquid, said gas discharging from the perforations 27 in the present disclosure. The core 29 thins the stream of liquid ascending through the pipe 11 and insures more thorough mingling of the gas and liquid than could otherwise be obtained. The initially intermingled gas and liquid are received in the mixer 30 and are jointly discharged from the latter into the upper portion of the container 14, through the perforations of the cap, such as 34 or 34^a, a second and more intimate mixture of gas and liquid being thus effected. The mixture of gas and liquid from the upper portion of the container 14, passes downwardly under pressure through the perforated partition such as 32 or 32^a and this partition effects a final mixing operation, producing a thoroughly carbonated liquid which discharges from the chamber 12 through the pipe 28. Obviously, no flow of liquid can take place through the apparatus until a spigot, draught arm, or the like connected with the pipe 28 is opened,

but upon such opening, flow of the liquid under pressure takes place and the carbonating gas is of course supplied at desired rate and pressure. I have found however that this 5 gas may be under an unusually low pressure, for instance forty pounds, whereas ordinarily the carbonating gas used with present carbonators, is maintained at a pressure around one-hundred and fifty pounds.

10 Particular attention is invited to the fact that the carbonator may be quickly and easily changed for producing either light or rich carbonation of liquids, whether they be thick, thin or more or less viscous. Then too, the 15 unusually simple and compact construction is a very desirable characteristic, allowing quick and easy disassembling for cleaning, changing mixers, etc. Moreover, the simple construction of the apparatus is such that it 20 may be made unusually small and light and hence is well adapted to domestic use, it being possible to install such apparatus in an ordinary refrigerator.

I claim:—

25 1. In a carbonator, a container having a carbonated liquid outlet and a removable portion spaced therefrom, a rigid liquid and gas conducting pipe terminating in said container and having a shoulder near its terminal, a hollow gas and liquid mixer detachably mounted upon said pipe terminal to receive the liquid and gas therefrom, and a perforated gas and liquid mixing partition extending across said container between said mixer 30 and said outlet, said partition removably being clamped between said mixer and said shoulder and having an opening through which said pipe passes, said mixer and said partition being accessible upon removal of 35 said removable container portion.

40 2. In a carbonator, a tank for the liquid to be carbonated, said tank having an inlet for gas under pressure, a liquid container supported by the top of said tank and having a 45 carbonated liquid outlet at its lower end, gas and liquid mixing means in said container, a pipe rising from the tank bottom into said container and leading to said mixing means for conducting liquid to the latter from said 50 tank, and means for conducting a carbonating gas into said pipe.

55 3. In a carbonator, a tank for the liquid to be carbonated, said tank having an inlet for gas under pressure, a liquid container supported by the top of said tank and having a carbonated liquid outlet at its lower end, gas and liquid mixing means in said container, a pipe rising from the tank bottom into said container and leading to said mixing means 60 for conducting liquid to the latter from said tank, said pipe having a swelled lower end to receive the liquid from the tank, and means for admitting a carbonating gas into said swelled pipe end.

65 4. In a carbonator, a tank for the liquid to

be carbonated, said tank having an inlet for gas under pressure, a liquid container supported by the top of said tank and having a carbonated liquid outlet at its lower end, gas and liquid mixing means in said container, a pipe 70 rising from the tank bottom into said container and leading to said mixing means for conducting liquid to the latter from said tank, said pipe having a swelled lower end to receive the liquid from the tank, means for admitting a carbonating gas into said swelled pipe end, and a core in said pipe to thin the 75 stream of liquid ascending therethrough and insure more thorough intermingling of the gas and liquid.

80 5. A carbonator comprising a lower container section closed at its lower end, open at its upper end and having a carbonated liquid outlet at said lower end, a vertical liquid and gas conducting pipe passing through said closed lower end of said lower container section and projecting above said open upper end of said lower container section, a perforated hollow spray head removably supported by and communicating with the upper 85 extremity of said liquid and gas conducting pipe, a perforated horizontal partition removably supported by said pipe below said spray head but above said open upper end of said lower container section, and an upper 90 container section closed at its upper end and having an open lower end, the latter being removably engaged fluid-tightly with said open upper end of said lower container section, said upper container section containing said perforated head and partition, whereby upon removal of said upper container section said head and partition may be readily removed and others substituted.

95 6. In a carbonator, a vertical liquid-conducting pipe having perforated discharge means at its upper end and an internally enlarged portion spaced downwardly from said discharge means, and a gas-conducting tube having a perforated gas discharge portion within said enlarged pipe portion, said tube extending upwardly within said pipe from its perforated portion, being spaced inwardly from the wall of the pipe and having a closed upper end, whereby said tube thins the liquid 100 stream in the pipe and insures mixing of the gas and liquid.

105 In testimony whereof I have hereunto affixed my signature.

SAMUEL M. DICK. 110
